(57) **CLAIM**

The ornamental design for a motor vehicle, toy and/or replicas thereof, as shown and described.

DESCRIPTION

FIG. 1 is a front and right side perspective view of a motor vehicle, toy and/or replicas thereof showing my new design; FIG. 2 is a rear and right side perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The wheels and lights shown on the vehicle throughout the drawing views in a de-emphasized and faded out half tone manner surrounded by broken lines defining the inward unclaimed boundaries are for environmental and illustrative purposes and form no part of the claimed design.
